UNITED STATES PATENT OFFICE.

BENJAMIN C. LORING, OF EDGEWOOD, RHODE ISLAND, ASSIGNOR TO JAMES TILLINGHAST, TRUSTEE, OF PROVIDENCE, RHODE ISLAND.

SANDING DEVICE.

No. 879,658.

Specification of Letters Patent.

Patented Feb. 18, 1908.

Application filed May 6, 1907. Serial No. 372,009.

To all whom it may concern:

Be it known that I, BENJAMIN C. LORING, a citizen of the United States, residing at Edgewood, in the town of Cranston, in the county of Providence and State of Rhode Island, have invented certain new and useful Improvements in Sanding Devices of which the following is a specification, reference being had therein to the accompanying drawing.

10 This invention relates to a sanding device for street cars and has for its object to provide a device which is simple and inexpensive in construction and effective in its operation.

15 It is found in practice in the operation of the ordinary rail sanding box carried by street cars that the jar of the car packs the sand so closely in the box that it will not run out when desired, even though the sand has been previously kiln dried.

20 To facilitate and assure the drawing of even closely packed sand from the box, I have provided a rotatable stirring device which may be readily passed through the 25 closely packed mass breaking it up and at the same time scraping it towards the valve opening whence it is delivered in the quantities desired to the rails in front of the wheels.

An essential feature of my construction is 30 that the means by which this stirrer is operated is carefully inclosed in a tight casing, whereby the sand is effectually prevented from getting into the mechanism to clog it up, and interfere with its working. Another 35 feature of this tight casing is that the wearing parts may be kept lubricated so as to insure a quick and easy action of the same.

A stirring device with blades set on an angle is particularly well adapted for this 40 purpose, the same being easy to rotate even in packed sand, as it has a natural tendency to move with a screw-like action the moment pressure is brought to bear upon it.

The invention is fully set forth in this 45 specification and more particularly pointed out in the appended claims.

In the accompanying drawings: Figure 1—is a side elevation showing a portion of a car in section, with my improved sanding 50 device located on the front platform of the car, the same being adapted to be operated by the foot of the motorman. Fig. 2—is an enlarged view of the rotating mechanism showing the same completely inclosed in a 55 protecting casing. Fig. 3—is a plan view

of the rotatable stirring device. Fig. 4—is a sectional side elevation of the same.

Referring to the drawings at 1 is the box or receptacle which may be located in any convenient place on the car. The same is 60 adapted to be filled through the hinged cover portion 2 in the upper end thereof. In this receptacle is located my improved stirring device which consists of a casing 3 secured in position through the bracket 4 to the front 65 portion of the car or side of the receptacle. The closing cap 5 is threaded into the upper end of the casing and is provided with an oil hole 6 through which the operating mechanism may be lubricated as often as desired. 70 This hole may be closed by means of the screw plug 7. At the lower end of this casing is a contracted shaft inclosing neck 8 which extends downward nearly to the bottom of the box. Fitting loosely in the 75 enlarged portion of this casing is the cylindrical portion 9 in which is formed the helical cam groove 10 which may extend about one-half way around the same. Threaded through the side of this casing is the pin 11 80 the inner end of which engages said cam groove, the same being secured firmly in position by the check nut 12. The coil spring 13 extends from the cap 5 to the top of this cylinder to press the same downward 85 and hold it normally in its down position.

At 14 is the valve or closing plug for the aperture 15 through the bottom of the box. To this valve is connected the stirring device 16 which is preferably formed with a plurality of thin blades set on an angle similar in construction to a fan, as illustrated in Fig. 3, but I do not confine myself to this precise construction as stirring arms of any form may be used if desired. This valve and 90 stirrer is connected to the cam cylinder through the upright shaft 17. This mechanism is adapted to be operated by the foot of the motorman through the removable pin 18, pivoted lever 19, and connection 20. 100 An enlarged pipe portion 21 is attached at 22 below the sand box on the underside of the car platform. This pipe is slotted at 23 in one side to admit one end of said pivoted lever 19 and permit its working therein. By 105 this arrangement the sand has no tendency to drop through the slot as the same is on its way from the valve opening through the pipe 24 to the rails 25.

In the operation of my improved device, 110

sand or dirt of any quality may be dumped therein and even though the same may pack to a considerable hardness the thin bladed fan-like stirrer will readily cut its way 5 through the mass, breaking the same up and scrape it towards and through the central aperture.

The most essential feature of my improved device is the introduction of the casing to 10 surround the whole to effectually prevent the clogging of the cam. It is obvious that in attempting to operate a device of this character in the sand box with a casing that in a short time, as soon as the sand becomes 15 packed it would be impossible to move it; then again, even though the same would move the cam and pin would soon be cut away by the action of the same as of course no lubricant could be applied to the working 20 parts.

By the use of my casing any lubricant may be admitted through the top of the same which will naturally work its way down through all of the working parts and finally 25 be carried out with the sand through the bottom of the box.

The device is very simple and practical of construction and effective in its operation, as by its use any desired amount of sand may 30 be quickly deposited on the rails.

Having thus described my invention, what I claim as new and desire to secure by Letters Patent, is:

1. In a sanding device, a sand receptacle 35 provided with an outlet through its bottom portion, a valve for controlling said outlet, a stirrer, an endwise movable shaft connected to said valve and stirrer, and means protected from the sand by which said shaft may be moved to rotate the stirrer to break up the sand, and also open said valve to deliver the sand therethrough.

2. A device of the character described comprising a sand receptacle provided with a bottom outlet, a valve for controlling said outlet, a stirrer, and means including a cam actuated shaft inclosed in a casing within said receptacle whereby said stirrer may be rotated to break up the sand and deliver the 50 same through said outlet.

3. A device of the character described comprising a sand receptacle provided with a bottom outlet, a valve for controlling said outlet, a stirring device having angular blades, 55 and means including a cam actuated shaft inclosed in a casing within said receptacle whereby said stirrer may be rotated to break up the sand and deliver the same through said outlet.

60 4. A device of the character described comprising a sand receptacle provided with a bottom outlet, a valve for controlling said outlet, a stirring device having blades, an end-

wise movable shaft connected to said valve and stirrer, and means protected from the sand by which said shaft may be moved to rotate the stirrer to break up the sand, and also open said valve to deliver the sand therethrough.

5. A device of the character described comprising a sand receptacle provided with a bottom outlet, a valve for controlling said outlet, a stirring device having angular blades, an upright shaft to which said stirrer is attached, and cam actuated means for rotating 75 said shaft and stirring device for facilitating the delivery of said sand through said outlet.

6. A device of the character described comprising a sand receptacle provided with a bottom outlet, a foot actuated valve for controlling said outlet, a stirring device having a plurality of thin radial blades said blades being set on an angle to a horizontal plane, an endwise movable shaft connected to said valve and stirrer, and means protected from 80 the sand by which said shaft may be moved to rotate the stirrer to break up the sand, and also open said valve to deliver the sand therethrough.

7. In a device of the character described 90 comprising a sand receptacle provided with a bottom outlet, a foot actuated valve for controlling said outlet, a stirring device constructed of thin radial blades, each blade being set at an angle to a horizontal plane, an upright shaft to which said stirrer is attached, and cam actuated means for rotating said shaft.

8. In a device of the character described comprising a sand receptacle provided with a bottom outlet, a foot actuated valve for controlling said outlet, a stirring device constructed of thin radial blades, each blade being set at an angle to a horizontal plane, an upright shaft to which said stirrer is attached, 100 cam actuated means for rotating said shaft and a casing within said receptacle in which said cam means is inclosed whereby the mechanism is protected from the action of the sand.

9. In a sanding device, a sand receptacle provided with an outlet through its bottom portion, a valve for controlling said outlet, a stirrer, an endwise movable shaft to operate 115 said stirrer to break up the sand, and means protected from the sand whereby the endwise movement of said shaft will cause the same to rotate and also open said valve to deliver the sand therethrough.

In testimony whereof I affix my signature 120 in presence of two witnesses.
